PRESS DEFLATING MECHANISM

John Frederick Smith, Quincy, Mass., assignor to
 Compo Shoe Machinery Corporation, New
 York, N. Y., a corporation of Delaware

Application January 31, 1935, Serial No. 4,272

5 Claims. (Cl. 12—36)

This invention relates to deflating mechanisms for use on multi-press machines having air operated presses. A particular and preferred application of the invention is to shoe press machines.

A general object of the invention is to provide a pressing machine having a movable carrier bearing a plurality of inflatable presses wherein improved means are provided for deflating each 10 of said presses at a determined part of the carrier traverse.

More specifically, objects of the invention are to provide an intermittently movable shoe press carrier with a positively acting deflating mechanism which is controlled so as to operate in desired time relation with the periods of movement and non-movement of the carrier.

A further object of the invention is to provide a shoe press carrier which is adapted to be driven intermittently, which has an air controlled deflating mechanism which is so interconnected with the control means for the carrier driving mechanism, as to effect deflation of presses only during periods of non-movement of the carrier.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and 35 objects of the invention reference should be had to the following detailed description taken in connection with the accompanying drawing, in which:

Fig. 1 is a fragmentary plan view of a shoe 40 press carrier or conveyor equipped with deflating mechanism embodying principles of the present invention;

Fig. 2 is a fragmentary front elevation of the right hand portion of the carrier shown in Fig. 1, parts thereof being broken away better to show 45 the structure; and

Fig. 3 is a transverse vertical sectional view taken substantially along line 3—3 of Fig. 2.

While benefits of the present invention may 50 be obtained generally with any form of multi-press carrier having inflatable and deflatable presses, it is particularly useful in connection with a shoe press conveyor of the kind shown, for example, in the United States patent to Weiss No. 1,945,762. For convenience of description,

the present invention is shown applied to and explained in conjunction with a shoe press machine of the kind shown in that patent.

With such conveyors a plurality of inflatable shoe presses are moved about an endless carrier 5 path past a loading station located at one determined portion of such path. Here the operator inserts in the press a shoe and sole having cement therebetween, and inflates the press so as to apply pressure to the sole and stick the 10 shoe parts together. After inflation the press proceeds about the carrier traverse in order to allow the cement to set while succeeding presses are being loaded. While being loaded, the press is held stationary at the loading station, so that 15 the movement of the carrier is intermittent. In order to save the operator the time and effort required to deflate a press arriving at the loading station, it is desirable to provide some means along the carrier traverse for automatically 20 deflating the press prior to its arrival at the loading station.

The present invention provides means for positively effecting opening the shoe press valves to effect deflation of each press prior to its arrival 25 at the loading station, and control means is provided whereby this deflating mechanism effectively operates on a press located in advance of the loading station during the period of non-movement in which the press at the loading 30 station is being handled. Other mechanisms suitable for performing such functions are described and claimed in my copending application Serial No. 4,271, filed January 31, 1935.

Referring more particularly to the drawing, 35 there is shown a carrier in the form of a flexibly elongate conveyor belt 10 which is adapted to pass around and be driven by rotatable drums (not shown), one of which is located at each end of the conveyor frame generally designated 40 11. These drums, or one of them, are adapted to be directly driven by an electric motor, not shown, so as to start movement when the motor current is turned on and to come to a drift stop when the current is cut off.

The belt 10 has a plurality of presses 12 mounted thereon at spaced intervals for movement therewith. Each press has an inflatable pad 13, which is adapted to be both inflated and deflated through an air valve 14, which has an outwardly 50 projecting spring biased plunger 15. This plunger operates in a well known manner to control the opening and closing of the valve seat, the latter being closed when the plunger 15 is in its outermost and normal position. One such 55

valve is shown, for example, in United States Patent No. 2,009,575, granted to William C. Card, Jr., on July 30, 1935. The press is further equipped with a suitable shoe supporting means 5 16, against which the inflatable pad is adapted to press a sole and upper assembly.

An air supply chuck 17 is located along the conveyor traverse in the loading station zone. It is preferably mounted for limited movement 10 along the carrier traverse by means of a slide-able carriage 18 mounted in brackets 19 affixed to the frame. This carriage is given a normal bias to the left (Fig. 1) by means of a spring 20, the progressive movement of the press on the 15 upper traverse of the conveyor being to the right as viewed in that figure. Each press carries a projecting lug 21, which is adapted to abut an arm 22 which is pivotally attached to the sliding carriage 18. As a moving press abuts and picks 20 up this arm it carries the air chuck 17 with it in registry with its valve 14. Such movement of the chuck and its associated carriage permits movement of a stopping switch 23 which cuts off the driving motor and brings the press to a drift 25 stop. This switch 23 is given a spring bias in a clockwise direction (Fig. 1) and is permitted to follow this bias when the carriage 19 reaches the approximate position shown in Fig. 1. In 30 this manner a press moving along the conveyor traverse toward the loading station is brought to a drift stop at such station with its valve in registered alinement with the air supply chuck 17. This chuck is movable toward the valve 14, being 35 slideable transversely of the carriage 18. Such movement is effected by means of a lever 24 which has one end pivoted to chuck 18 and is fulcrumed intermediate its ends on a bracket affixed to the carrier frame. Its other end is attached to a link 25 for movement thereby and 40 this link is pivoted through the agency of a bell crank lever 26 to a treadle operated link 27 so that depression of the treadle will effect movement of the air chuck toward and into communicative contact with the press valve 14. The bell 45 crank lever 26 is freely rotatable about a horizontal shaft 28 which is fixedly mounted on the carrier frame by means of suitable brackets. This drift stop and inflation mechanism is substantially like that described in the above mentioned Weiss patent 1,945,762 and does not form 50 a part of the present invention except in so far as it is used in combination therewith.

The means for effecting deflation of each press before it is thus brought to a drift stop at the 55 loading station comprises, in accordance with the present invention, a deflating plunger including a deflating bar 29 which is fixedly attached to one end of the plunger proper 30. The bar 29 is preferably of such length as to 60 span the valves of two adjacent presses as they are brought to a stop opposite it. Such bar may be located at any suitable portion of the conveyor traverse in advance of the loading station, being shown in Fig. 1 as being opposed to 65 the second and third presses in advance of the one opposite the air inflation chuck.

The plunger 30 carries at its inner end an air piston 31 which operates in an air cylinder 32. An air inlet port 33 is located in this cylinder on 70 the side of the piston toward the carrier so that admission of air to the cylinder will retract the plunger bar 29 from the path of the valve plungers 15. A spring 34 gives the deflating plunger a normal bias toward the valve plungers, and 75 brings such bar into deflating relation with an

opposed valve except when it is held retracted through operation of the piston 31.

This piston is adapted to be retracted in timed relation with the periods of movement and non-movement of the presses. To this end air is 5 admitted into the cylinder through a valve 35 which communicates with port 33 through an air conduit 36. The valve 35 is adapted to be opened at such time as the driving motor for moving the conveyor is started. A switch 37 controls 10 the starting of this motor. This switch is given a normal spring bias in a clockwise direction (Fig. 3) and is adapted to be turned against its bias by a rotatable cam 38 forming one arm of a bell crank lever.

The other arm 39 of this lever is connected to a treadle link 40 which is adapted to be depressed by a treadle 41 so as to swing the switch 37 to motor starting position. An arm 42 is also united to, for movement with, bell crank arms 38 and 39 20 and it extends inwardly into abutting contact with an operating lever 43 for the deflating air cylinder valve 35. The connected arms 38, 39, and 42 are freely rotatable on shaft 28, so that depression of treadle 41 will simultaneously effect 25 starting of the motor and opening of the valve 35, without affecting the press inflating mechanism at 26, etc.

By means of such structure, air is admitted to cylinder 32 at the same time that the presses 30 begin their movement after any given loading operation, and the deflating plunger 29—30 is quickly retracted from its deflating engagement with the press valves 14. In order again to bring the deflating plunger into contact with 35 successively opposed valves during the subsequent period of non-movement of the press, a bleeder orifice 44 is provided in cylinder 32 and this orifice is made of such size as to permit spring 34 again to bring the deflating plunger 40 into the path of the press valves at or shortly after the presses again come to rest through operation of drift stop switch 23, which, as explained, operates to cut off the motor which 45 was started by switch 37.

In using the present equipment, an operator situated at the loading station loads a lasted upper and a registered outer sole having cement therebetween into a press which has come to a drift stop opposite air chuck 17. He then inflates the press by depressing treadle lever 27 and bringing the chuck into communication with the press valve 14. After the press is inflated he steps on the starting treadle 41, starting the conveyor driving motor and admitting air into deflating plunger cylinder 32. This plunger is thus retracted while the presses are moving, and this press movement continues until the lug 21 on the next press of the carrier picks up the arm 22 and slides the chuck carriage 18 so as to operate 60 the stop switch 23, again bringing the presses to a stop. At about this time the bleeder orifice 44 in the deflating cylinder will have vented the air therein, allowing the bar 29 to contact and depress the opposed valve plungers 15. It will 65 be noted that this bar 29 is of such extent, and is so located with reference to the loading station, that it opposes two adjacent press valves. Thus, each press is subjected to two deflating periods, so that it undergoes a longer deflating 70 period than that used for inflation. This assures complete deflation of each press as it reaches the operator at the loading station, and enables him readily to remove a cemented shoe therefrom in order to reinsert a new sole and upper 75

assembly. If desired, however, the plunger may be designed so as to contact only one press at a time, or any desired plurality of presses as well as the two illustrated may be contacted.

5 It will be seen that there has been provided an apparatus which is well suited to fulfil its intended functions. Since certain changes may be made in the above construction and different embodiments of the invention could be made 10 without departing from the scope thereof, it is intended that all matter contained in the above description or shown in the accompanying drawings shall be interpreted as illustrative and not in a limiting sense.

15 It is also to be understood that the following claims are intended to cover all of the generic and specific features of the invention herein described, and all statements of the scope of the invention which, as a matter of language, 20 might be said to fall therebetween.

Having described my invention, what I claim as new and desire to secure by Letters Patent, is:

1. A machine of the class described, comprising a carrier, a plurality of inflatable presses mounted on said carrier for intermittent movement along its traverse, an air control valve on each press, means for inflating said presses, a deflating plunger movable into and out of deflating relation with said valves, an air operated piston 25 for moving said plunger, and means for automatically applying air to said piston to move said plunger out of deflating position in timed relation with said carrier movement.

2. A machine of the class described, comprising a carrier, a plurality of inflatable presses mounted on said carrier, an air control valve on each press, means for inflating said presses, a deflating plunger movable into and out of deflating relation with said valves, an air operated 30 piston for moving said plunger, means for inter-

mittently driving said carrier, and common control means for actuating said carrier driving means and said piston.

3. A machine of the class described, comprising a carrier, a plurality of inflatable presses 5 mounted on said carrier, an air control valve on each press, a movable deflating plunger spring biased into deflating relation with said valves, an air cylinder and piston operable to retract said plunger, and means for admitting air into 10 said cylinder to retract said plunger from deflating position when said carrier is moved.

4. A machine of the character described, comprising a carrier, a plurality of inflatable presses 15 mounted on said carrier, an air control valve on each press, a deflating plunger movable into and out of deflating relation with said valves, an air cylinder and piston operable to retract said plunger, means for starting movement of said carrier, and means for admitting air into said 20 cylinder to move said plunger out of deflating relation when said carrier starting means is actuated.

5. A machine of the character described, comprising a carrier, a plurality of inflatable presses 25 mounted on said carrier, an air control valve on each press, means for inflating said presses, said carrier being intermittently movable successively to present presses at said inflating means, a deflating plunger biased into deflating relation with an opposed valve, an air cylinder and piston operable to retract said plunger, means for admitting air into said cylinder approximately at the inception of movement of said carrier, and a bleeder valve for discharging the air from said 30 cylinder at a rate permitting said plunger to assume deflating relation with a succeeding valve approximately at the end of such carrier movement.

JOHN FREDERICK SMITH. 40
